UNITED STATES PATENT OFFICE.

CHARLES O. GREGORY, OF CENTREVILLE, MICHIGAN.

GIG-TREE AND ATTACHMENTS.

SPECIFICATION forming part of Letters Patent No. 369,707, dated September 13, 1887.

Application filed July 5, 1887. Serial No. 243,421. (No model.)

To all whom it may concern:

Be it known that I, CHARLES O. GREGORY, a citizen of the United States, residing at Centreville, county of St. Joseph, State of Michigan, have invented a new and useful Gig-Tree, of which the following is a specification.

This invention has for its object certain features of construction and association of parts for detachably coupling the rein-hook with the gig-tree of a harness.

In the drawings forming a part of this specification, Figure 1 is a perspective view; Fig. 2, an under plan view, and Fig. 3 a section on line 1 1 in Fig. 2.

Referring to the letters of reference marked on the drawings, B is an ordinary gig-tree. In the under side is a dovetail mortise, into which is detachably inserted the dovetail end *a* of the rein-hook D. To effect this insertion of the hook a mortise is formed just back of the dovetail mortise, at right angles thereto, and communicates with it. A block of leather or other material, *c*, of a size to fill the latter-described mortise is detachably inserted therein, and this prevents the hook D from working back and becoming loose and accidentally falling out. The mortise in which the block *c* is inserted is between the crupper-loop *u* and the end of the rein-hook D, and is of course on a curve with the curve of the gig-tree.

In Fig. 3 the dark part of the block *c* is in section and the lighter part shows beyond, because it is concave on the under side; but this particular shape is not essential.

If a hook breaks, it can be readily replaced 35 without ripping the harness-saddle beneath the gig tree and without the removal of rivets or bolts. If there was otherwise danger of the block *c* coming out of its mortise, the saddle or straps beneath the gig-tree (not here shown) 40 would keep it in place.

Having thus described my invention, what I claim is—

In combination, a gig-tree having the dovetail mortise, a communicating recess at the end 45 of said mortise, a rein-hook shaped to detachably fit the dovetail mortise, and a block fitting into the recess at the end of the hook to retain the latter in place, substantially as set forth.

In testimony of the foregoing I have hereunto subscribed my name in presence of two witnesses.

CHARLES O. GREGORY.
